UNITED STATES PATENT OFFICE.

HARRY E. ASBURY AND EDWARD E. PUNZELT, OF PHILADELPHIA, PENNSYLVANIA,
ASSIGNORS TO THE ENTERPRISE MANUFACTURING COMPANY OF PENNSYLVANIA,
OF PHILADELPHIA, PENNSYLVANIA, A CORPORATION OF PENNSYLVANIA.

DESIGN FOR A CASING OF A COFFEE-MILL.

49,324.

Specification for Design.

Patented July 11, 1916.

Application filed February 24, 1915. Serial No. 10,377. Term of patent 14 years.

To all whom it may concern:

Be it known that we, HARRY E. ASBURY and EDWARD E. PUNZELT, citizens of the United States, and residents of Philadelphia, county of Philadelphia, State of Pennsylvania, have invented a certain new, original, and ornamental Design for the Casing of a Coffee-Mill, of which the following is a specification, reference being had to the accompanying drawing, forming part thereof.

The figure is a perspective view of a cas-

ing of a coffee mill, showing our new design.

We claim:

The ornamental design for the casing of a coffee mill substantially as shown in the accompanying drawing.

HARRY E. ASBURY.
EDWARD E. PUNZELT.
